UNITED STATES PATENT OFFICE.

GEORGE COLVIN KENNEDY, OF WATERLOO, IOWA.

MAUSOLEUM.

1,333,423.

Specification of Letters Patent.

Patented Mar. 9, 1920.

Application filed July 14, 1916. Serial No. 109,291.

To all whom it may concern:

Be it known that I, GEORGE COLVIN KENNEDY, a citizen of the United States of America, and a resident of Waterloo, Black-hawk county, Iowa, have invented certain new and useful Improvements in Mausoleums, of which the following is a specification.

My invention relates to improvements in 10 mausoleums, and the object of my improvement is to supply crypts made in knock-down sections arranged for easy assemblage as needed, and inexpensive in construction. Other objects will be more specifically 15 pointed out hereinafter.

The above objects I have accomplished by the means which are hereinafter described and claimed, and which are illustrated in the accompanying drawings, in which 20 Figure 1 is a front end elevation of a number of assembled crypts, some of the crypts having parts sectioned away or removed; Fig. 2 is a side elevation of the inner side walls on one side of two assembled and 25 superposed crypts, parts of the crypts being broken away, and the view being taken on the line *a*—*b* of said Fig. 1; Fig. 3 is a cross-section of one of the side sections of a crypt, taken intermediate its ends; Fig. 4 is 30 an enlarged detail cross-section of a joint between two superposed side sections and interposed floor sections; Fig. 5 is a cross-section of a floor plate, taken intermediate of its ends; Fig. 6 is an outside end view of 35 the abutting sealing-flanges on the ends of adjacent side and floor-plates; Fig. 7 is an enlarged detail sectional view of the sealing means and mounting for adjacent front end closures and their face-plates, and Fig. 8 is 40 a section of the rear part of a crypt, including the rear end-closure. Fig. 9 is a cross-section of a floor-plate like that shown in Fig. 5, but inverted.

Similar numerals of reference denote corresponding parts throughout the several views.

One of my improved knockdown mausoleum crypts comprises detachably connected side sections 1, like floor and roof or top sections 6, front and rear end-closures 14 and 50 26, and face-plates 25 for covering the front ends of the crypts.

Each of the like side sections 1 consists of a plate of suitable material, preferably metal, as cast-iron, having at top and

bottom longitudinal horizontally disposed flanges 3 on opposite sides, the flanges having bolt-holes at intervals to receive the double-ended headless bolts 5 which, with the nuts 4 at either end secure the side sections 1 to the floor and top sections or plates 6, the bolts passing through registering holes in the plates 6. The longitudinal edge portions of these top and bottom sections 6 are inserted between the adjacent like 65 flanges of superposed side-plates, as shown in Fig. 4, and if it is desired to form a hermetically sealed joint or joints between these parts, a thin plate of lead or other suitable sealing material 7 is interposed between them, so that under compression the yielding sealing material will close up all 70 crevices due to any irregularities of surfaces abutting against such means.

The top and bottom plates or sections 6 75 may be flat, but I prefer to give them an arched form in order to render them very stiff and rigid with a minimum consumption of material. I have therefore shown these plates medially slopingly offset at 8 (see 80 Fig. 5), to furnish a flat middle raised part 9 extending longitudinally along the middle longitudinal line of the crypt. Another important use is found in this method of construction, in the employment of the tabular part 9 to support a casket 28 above the bottom of the crypt. In its elevated position, the casket is more accessible, and furthermore, any liquids seeping through the casket will escape downwardly over the 85 sloping surfaces of the obliquely offset parts 8 of the floor in a thin layer, which will evaporate more quickly, and be more subject to deodorizing and disinfecting preparations introduced into the crypt or left there 90 at the time the casket is deposited there. The plate 9 may be inverted, as shown in Fig. 9, and used the same way. If desired, a threaded orifice may be furnished in the upper part of the rear-end closure 26, to receive a vent-pipe 27, whereby any vapors or 95 gases may be conducted away to a suitable apparatus for treatment before being voided into the atmosphere.

The side-sections 1 may be strengthened 105 against compressive strain by means of integral vertical ribs 2 on each side placed at intervals, as required.

The crypt thus formed is very rigid, since 110 the flanges 3 of the side sections 1 provide

wide bearings for the longitudinal edges of the top and floor plates, while the arched top and floor plates resist torsional strains.

The end-closures 14 and 26 are alike in all respects, each consisting of a plate of metal provided with marginal outwardly-directed flanges 15. Double-ended headless bolts 16 passed through registering bolt-holes in the flanges and the abutting parts of the side and top and bottom sections, with nuts 17, secure the closures detachably in the ends of the crypt. In case it is desired to hermetically seal the joints of the closures with said sections, the following sealing-means are used, referring to said Fig. 7.

Each end-closure has formed on its inner face marginally a rib 18 extending all around it and abutting closely upon like ribs formed integrally on the adjacent portions of the side and top and bottom sections, as shown at 19. These ribs preferably meet on a slope to permit of readily seating the closures in the ends of the crypt, and the abutting faces of the ribs are supplied with longitudinal grooves of semi-elliptic cross-section. A strip of compressible material, such as lead, of circular cross-section, as shown at 20 is placed in the elliptic channel formed in the abutting ribs, and when the nuts are tightened on the bolts 16, the ribs are drawn together, or rather, the rib 18 is drawn toward the rib 19, compressing between them the sealing strip 20 which seals the interspace by becoming deformed to fill any irregularities, the extra space in the elliptic channel permitting this.

The numeral 25 denotes a face-plate, upon which may be placed an inscription, and which has bolt-holes 24 through which to pass cap-screws 23, the threaded ends of the latter fitting interiorly-threaded sockets 22 formed on the outer face of the front clo-

sure 14. Any face-plate may be removed without disturbance of other face-plates abutting upon it.

45

The bottom tier of crypts may be supported solidly upon T-bars 29 positioned longitudinally under a base-bar 30 at each side of a crypt, the base-bar answering to the flanged parts of the side section 1 thereabove for securing purposes, and a similar top-bar 31 may be used at the top of a vertical tier of crypts, although not absolutely necessary.

50

Since all the joints of the crypt are hermetically sealed, there is no possibility of a leakage of gases into the atmosphere, and deodorizing and disinfecting gases of an otherwise deadly nature may be employed in a crypt for preserving remains therein, without discomfort or danger to persons in the vicinity.

55

Various minor changes may be effected in the form, dimensions and arrangements of the parts of my improved knockdown mausoleum crypts, without, however, departing from the principle of this invention, or the proper scope of its protection.

60

Having described my invention, what I claim as new, and desire to secure by Letters Patent is:

65

In a cellular structure of the class described, having detachably connected side, top and bottom wall plates; like top and bottom plates for each cell shaped integrally with a part offset at a different level than another part, to provide a liquid-gathering receptacle at the bottom and a restricted gas-collecting receiver at the top of each cell.

70

Signed at Waterloo, Iowa, this 12th day of July, 1916.

75

GEORGE COLVIN KENNEDY.
